EXERCISER

Karl H. Herrmann, 7318 Dibble Ave. NW, 98107, and Hans H. Herrmann, 510 NW 195th 98177, both of Seattle, Wash.

Filed June 26, 1972, Ser. No. 266,487

Term of patent 14 years

Int. Cl. D21—02

U.S. Cl. D34—5 K

Fig. 1.

Fig. 2.

Fig. 3.

Fig. 4.

FIG. 1 is a top, front and left side perspective view of an exerciser showing our new design;

FIG. 2 is a top plan view thereof, the bottom being substantially plain and unornamented;

FIG. 3 is a front elevational view thereof, the handle being omitted for convenience of illustration, the rear view being substantially similar thereto;

FIG. 4 is a right side elevational view thereof.

We claim:

The ornamental design for an exerciser, as shown and described.
